FIG. 1

FIG. 2

FIG. 3

FIG. 4

FIG. 5

FIG. 1 is a front perspective view of a seat showing my design in the form of a davenport;

FIG. 2 is a side elevation of the trimmed seating element illustrated in FIG. 1;

FIG. 3 is a rear elevation of the trimmed seating element illustrated in FIG. 1;

FIG. 4 is a front perspective view of the trimmed seating element illustrated in FIG. 1, shown in the form of a love seat; and

FIG. 5 is a perspective view of the seat also shown in the form of a love seat but wherein the arm design has been modified.

The sides of the davenport and love seat not shown are identical to those which are shown.

I claim:

The ornamental design for a seat, substantially as shown and described.
